UNITED STATES PATENT OFFICE.

ERNEST VELTUNG AND JACOB VELTUNG, OF NEW YORK, N. Y.

HARNESS-PAD.

SPECIFICATION forming part of Letters Patent No. 685,541, dated October 29, 1901.

Application filed August 21, 1900. Serial No. 27,552. (No model.)

To all whom it may concern:

Be it known that we, ERNEST VELTUNG and JACOB VELTUNG, citizens of the United States, and residents of New York city, in the county of New York and State of New York, have invented a certain new and useful Improvement in Harness-Cushions, of which the following is a specification.

Our invention relates more particularly to elastic pads or cushions for horse-collars, harness, and the like, the main objects of the invention being to secure strength and durability of the pad or cushion and also ventilation thereunder while in use.

In the practice of our invention we sometimes take a piece of cloth, leather, or other suitable material, double it, and then form a series of pockets extending transversely of the same, as by sewing or otherwise, closing one end of said pockets either by folding the cloth, leather, or the like or by stitching or otherwise. For convenience we shall term this article a "bandolier," and we remark that its ends may or may not be fastened together, as desired or convenient. Then we force into each pocket one or more inflated elastic hollow balls, as soft-rubber balls, and then we close the open ends of the pockets by stitching or otherwise. It is preferable that these pockets be of a size such that the balls have to be forced into them by hand or otherwise, thus putting the balls under some outside pressure to start with. In use this cushion is placed between some rigid part or wearing-piece and the skin of the animal, and by its flexibility it conforms to the shape of the animal.

When the cushion is to be used as a part of a collar, it may be fastened permanently to wooden or metal bearing-pieces, which may be hinged together or which may be substantially in one piece, to be slipped over the horse's head.

Our invention consists in features of construction and combinations of devices herein described, and more particularly pointed out in the appended claims.

The preferred form of the invention is illustrated in the accompanying drawings, forming part of this specification, in which—

Figure 1 is a rear view of a horse-collar in which the invention is embodied. Fig. 2 is

an enlarged detail view, partly in section, on a plane passing between the balls shown in Fig. 3. Fig. 3 is a cross-section of the collar shown in Fig. 1, the section being taken along one of the bands or fasteners. Fig. 4 is a detail view of part of the bandolier, showing lines of stitching, (dotted lines.)

In the drawings the reference *a* marks a metal or, what is preferred, a wooden wearing or strengthening piece forming part of the collar, *b* the rabbet for receiving the hame, and *c* a lining of suitable material—as leather, felt, cloth, or the like—between the wearing piece *a* and the cushion *C*.

The cushion *C* comprises a fabric *d*, as "pantasote," an artificial leather consisting of a woven fabric covered on one side with a flexible and durable paint or coating, doubled and stitched to provide a series of pockets *e*, within which hollow soft-rubber balls *f* are placed. The pockets need not all be of one size, and the same is true of the balls *f*. The balls *f* are inflated, so as to be fairly stiff. We find that for horse-collars the balls should be about as firm as ordinary tennis-balls; but we do not of course limit ourselves to any particular degree of firmness in the balls. We find that it is better to have the pockets of such size that the balls have to be forced into them by considerable effort on the part of the workman.

In the instance illustrated in the drawings there are two balls *f* in each pocket, and the fabric *d* is drawn down between the rows of balls and is tacked to the wood at the edges of the bandolier, the tacks being marked *g*. At intervals we may put additional fasteners, as bands *h*, which are held in place by the tacks *i*, said additional fasteners *h* lying in valleys or wrinkles over rows of stitches between adjacent pockets *e*. It will be noted that the tacks *g* are placed in the form of the invention illustrated in the drawings at the corners of the pockets. This is merely the preferred arrangement, however, for the tacks may be placed elsewhere.

It will be observed that the collar is corrugated transversely. We find in practice that these corrugations form efficient means for ventilating under the collar when it is in use, while the elastic nature of the cushion *C* saves the neck and shoulders of the animal. Other

advantages of the invention will be apparent to those skilled in the art.

We do not limit ourselves to the precise form of our invention shown in the drawings 5 and above described, since the embodiment thereof may be varied greatly without departing from the spirit of the invention.

What we claim as new, and desire to secure by Letters Patent of the United States, is—

- 10 1. A cushion or pad for harness and the like consisting of a plurality of side-by-side pockets formed of flexible inelastic material and independent air-cushions in and held under compression by such pockets.
- 15 2. In a horse-collar or the like, the combination with a wearing or stiffening piece, of a plurality of side-by-side pockets attached to said piece, said pockets being formed of flexi-

ble inelastic material, and independent air-cushions in and held under compression by 20 said pockets.

3. A pad or cushion for harness and the like consisting of a bandolier of flexible inelastic material folded upon itself along a central line and fastened transversely at intervals to 25 form the pockets, and independent air-cushions in and held under compression by such pockets, substantially as described.

Signed at New York, in the county of New York and State of New York, this 18th day 30 of August, A. D. 1900.

ERNEST VELTUNG.
JACOB VELTUNG.
